UNITED STATES PATENT OFFICE.

CLEMENT D. O'ROURKE, OF DAYTON, OHIO.

DESIGN FOR A COMBINED NEWSPAPER-VENDING BOX AND TRASH-RECEPTACLE.

58,816.

Specification for Design.

Patented Aug. 30, 1921.

Application filed March 12, 1921. Serial No. 451,819. Term of patent 3½ years.

To all whom it may concern:

Be it known that I, CLEMENT D. O'ROURKE, a citizen of the United States, residing at Dayton, in the county of Montgomery and State of Ohio, have invented a new, original, and ornamental Design for a Combined Newspaper-Vending Box and Trash-Receptacle, of which the following is a specification, reference being had to the accompanying drawing, forming part hereof.

The figure is a perspective view of a com-

bined newspaper vending box and trash receptacle, showing my new design.

I claim:

The ornamental design for a combined newspaper vending box and trash receptacle, as shown.

CLEMENT D. O'ROURKE.
